UNITED STATES PATENT OFFICE.

FRANK A. SMITH, OF CHICAGO, ILLINOIS.

DIME-BANK.

1,269,870.

Specification of Letters Patent. Patented June 18, 1918.

Application filed December 20, 1917. Serial No. 208,067.

To all whom it may concern:

Be it known that I, FRANK A. SMITH, a citizen of the United States, and a resident of Chicago, in the county of Cook and State of Illinois, have invented a new and useful Improvement in Dime-Banks, of which the following is a specification.

My invention is an improvement in dime banks, and has for its object to provide a device of the character specified for holding a predetermined number of dimes, so that they will be visible but cannot be removed until the box is unlocked by a particular form of key.

15 In the drawings:—

Figure 1 is a front view showing the manner of inserting the coin,

Fig. 2 is a perspective view, looking at the front,

20 Fig. 3 is a similar view, looking at the back,

Fig. 4 is a section on the line 4—4 of Fig. 2, looking in the direction of the arrows adjacent the line,

25 Figs. 5 and 6 are sections on the lines 5—5 and 6—6 respectively of Fig. 3, both views looking in the direction of the arrows adjacent the line,

Fig. 7 is a perspective view of the box with 30 the cover removed and looking at the inside,

Fig. 8 is a similar view of the cover looking at the inner side,

Fig. 9 is a perspective view of the unlocking device or key.

35 In the present embodiment of the invention a box is provided comprising a box body 1 and a cover 2. The box body is formed from a sheet of suitable material having the side edges and one end bent over upon the

40 body in spaced relation to form inwardly extending flanges 3 at the said sides and end. The cover is adapted to be slid between the flanges 3 and the body, and the body has a series of openings 4 at each side of its center

45 for permitting the coins to be seen while in place in the box. The coins are slipped in at the open end of the box and it will be noticed that there are notches or recesses 5 at the said ends, each notch being in line with the adjacent series of openings 4.

The inner end of the cover has an inward flange and the said flange has a portion at the center of the cover removed to form a notch 7 in the flange. The locking means for 50 the box is adapted to engage this flange to

lock the cover in place, and the said means comprises a wire 8 bent into the form of a hairpin and secured to the inner face of the box body bottom, on each side of a rib 9 extending longitudinally of said body at the center thereof. The body of the hairpin-shaped lock is at the open end of the box, and arms lie upon either side of the rib and are secured thereto in any suitable manner as for instance, by soldering.

65

The free ends of the arm diverge slightly, sufficiently to cause them to bear against the flange 6 on each side of the notch 7, as shown more particularly in Fig. 6, thus to lock the cover in place. The rib and the 70 hairpin-shaped lock form in addition a separating and holding means for the coin, so that the coins at one side cannot pass over to the opposite side. The cover has struck-up lugs 10 at the end adjacent to the open end 75 of the body, the said lugs extending inwardly and two pairs of lugs are provided, one pair on each side of the center.

The cover has depressed portions 11 at its center and these notches or depressions are 80 adapted to engage the rib 9 to hold the cover up tightly against the flanges 3. A key 12 is provided for unlocking the box. This key is a substantially U-shaped member, and the free end of each arm is provided with an inwardly extending lug 13. The free ends of the arms are adapted to pass through openings 14 in the cover and the said openings are so arranged that when the arms of the key are inserted the lugs 13 will be on opposite sides of the locking member at the outer side of the arm. These slots 14 are of sufficient width to permit a limited movement of the key arms, sufficient to spring the arms of the locking member inward to release 95 them from the flange 6 and to bring them into registry with the notch 7.

In use the coins are slipped into the box at the open end thereof and as each coin is inserted those in front of it are pushed farther toward the closed end of the box. When the box is filled it may be unlocked by means of the key. The improved banks are especially adapted for savings banks to encourage saving, and the key may be retained at 105 the bank in order that they will not be unlocked until they are brought to the bank.

I claim:—

1. A device of the character specified comprising a box body and a cover, the body 110

2

having its side edges and one end turned over upon the body to form flanges at said sides and end arranged in spaced relation with respect to the body, the cover being 5 slidable between the flanges and the body, said cover having at its inner end a flange extending toward the bottom of the body, said flange being notched at its center, a U-shaped locking member secured to the 10 body at the center thereof and extending toward the closed end and having resilient arms diverging slightly to engage the flange of the cover on each side of the notch, said cover having openings at the said diverging arms for permitting the insertion of a key for pressing the said arms toward each other.

2. A device of the character specified, comprising a box body having one end open, and 20 a cover slidably connected with the body for closing the top of the same, said cover having an inturned flange at its inner end and the body having locking means for engaging the flange, the flange having a cut- 25 away portion at its center and locking means consisting of resilient arms engaging the flange at opposite sides of the cut-away portion, the cover having openings at the arms for permitting the insertion of a key to press 30 the arms toward each other, said cover having means at the open end of the box for

permitting the entrance of a coin and for preventing the return of the coin.

3. A device of the character specified, comprising a box body having one end open, 35 and a cover slidably connected with the body for closing the top of the same, said cover having an inturned flange at its inner end and the body having locking means for engaging the flange, the flange having a cut-away portion at its center, and locking means consisting of resilient arms engaging 40 the flange at opposite sides of the cut-away portion the cover having openings at the arms for permitting the insertion of a key 45 to press the arms toward each other.

4. A device of the character specified, comprising a box body having a sliding cover provided at its inner end with an in-turned flange, the flange being cut away at 50 its center, resilient arms secured to the box body and engaging the flange at opposite sides of the cut away portion when the cover is closed, the cover having openings near its inner end at the outer sides of the arms for 55 permitting the insertion of a key to press the arms toward each other to release them from the flange.
